FIG.3

FIG.4

FIG. 1 is a right front perspective view of a cash register or similar article showing my new design;

FIG. 2 is a left front perspective view of the cash register or similar article with the supporting and drawer-carrying stand portion thereof broken away to permit enlarged showing of the dominant features of my design;

FIG. 3 is a top perspective view; and

FIG. 4 is a rear perspective view thereof.

The dominant features of my design reside in the full-line portions of the drawings.

I claim:

The ornamental design for a cash register or similar article, as shown and described
